UNITED STATES PATENT OFFICE.

JOSEPH W. KAUGH, OF DALLAS, TEXAS.

WRENCH.

Application filed December 2, 1922, Serial No. 604,595. Renewed November 21, 1923.

To all whom it may concern:

Be it known that I, JOSEPH W. KAUGH, a citizen of the United States, residing at Dallas, in the county of Dallas and State of Texas, have invented certain new and useful Improvements in Wrenches, of which the following is a specification.

This invention relates to new and useful improvements in wrenches.

10 The invention has particularly to do with that type of wrench which is designed for use on pipes, well casing and tool joints or other cylindrical objects which are usually in a perpendicular position.

15 The object of the invention is to provide a wrench which is adapted to be self-closing and self-latching and including a pair of gripping and clamping members constituting jaws.

20 A further object is to provide a wrench wherein a pair of jaws are arranged so as to close and grip the article when brought into contact therewith and also to latch; together with an eccentric controlled by a 25 handle so as to increase the gripping or clamping action after the jaws have been latched.

25 A still further object is to provide a pair of gripping jaws one of which is pivoted in the wrench head and the other of which is hinged to the first named jaw, the last 30 named jaw being self-latching and the first named jaw co-acting with a displacing element, whereby an article is firmly clamped 35 in the jaws.

Another object is to provide a pair of gripping jaws hinged together and pivoted in the head so as to undergo a relative sliding or circumferential movement when displaced to clamp the pipe.

A still further object of the invention is to provide in one embodiment of the invention, a pair of gripping jaws arranged so that one upon being brought into contact 45 with the article swings the other to a closed position in which it is latched, the first named jaw being free to undergo separate clamping action after the last named jaw has been latched.

50 A construction designed to carry out the invention will be hereinafter described together with other objects of the invention.

The invention will be more readily understood from a reading of the following specification and by reference to the accompany-

ing drawings, in which an example of the invention is shown and wherein:

Fig. 1 is a side elevation of a wrench constructed in accordance with my invention;

Fig. 2 is a plan view of the same,

Fig. 3 is a detail of the latching means,

Fig. 4 is a detail of the knuckle joint,

Fig. 5 is a fragmentary view of a modification, and

Fig. 6 is a fragmentary view of another modification.

In the drawings the numeral 10 designates a head comprising cheek plates 11 connected at one side by a web 12 and at the other side by a web 13, thus providing a space between the plates extending longitudinally thru the head. The head has a concaved seat 14 at its forward portion at one side of which the web 13 extends to the extremity of said head to form a lug 15; while at the other side of the seat the web 12 is cut away so that each plate is formed with a corresponding ear 16.

An arcuate actuating jaw 17 is fulcrumed on a pin 18 extending thru the ears and has its gripping surface substantially contiguous to the seat 14, while its outer end extends beyond the ears and is hinged in the bifurcated end of an arcuate gripping jaw 19 to which it is connected by a pin 20. The gripping faces of the jaws have substantially the same radius, which is less than that of the article to be gripped. The free end of the jaw 19 is provided with a latch hook 21 which is shaped to ride into a latch keeper 22 which straddles the lug 15 and is pivoted on a pin 23 passing therethru.

The keeper has a handle 24 at its outer end whereby it may be swung off of the hook to free or release the jaw 19. The end of the lug 15 has a concentric face 25 and a transverse pin 26 mounted in the yoke end of the keeper rides over said face when the keeper is swung. The inward or latching movement of the keeper is limited by the engagement of the said pin with a stop shoulder 27 (Fig. 3) on the lug. In order that the latch keeper may be normally held in a latching position with the pin in engagement with the shoulder, a yoke spring 28 embraces the lug 15 and has its legs attached to each side of the keeper outwardly of the pivot pin 23, each of said legs being coiled about said pin. The keeper is thus placed under tension and

is provided with a transverse latch bar 29 which is under cut. The hook has its face curved so as to ride over the bar 29 and displace the keeper outwardly until said hook passes below the bar, whereupon the keeper is swung inwardly so that the hook engages under the bar and the jaws are fastened. It will be seen that the hook does not contact with the lug, thus leaving sufficient play for 10 the hook to be swung inwardly when it is desired to release the keeper.

In Figs. 2 and 4 the jaws are shown in their open position in dotted lines and it will be noted that the jaw 17 is thus in advance of the seat 14 and the jaw 19 is open sufficiently to admit the pipe between the same and the keeper. When the wrench is moved toward the pipe, the latter term being used generically, the function of the actuating jaw 17 is to engage the pipe and when swung inwardly, to swing the gripping jaw into engagement with the latch keeper, thus fastening the wrench on the pipe. To accomplish this each plate 11 is provided 25 with a knuckle 30 on its extremity positioned to be engaged by a finger 31, the latter being formed on each of the furcations of the jaw 19. The fingers and knuckles are located between the pivot pins 18 and 20.

When the jaw 17 is swung inwardly it is moved about its pivot pin 18, the knuckles being in fixed relation to said pin and stationary. The outer end of the jaw 17 thru the agency of the pin 20 swings the jaw 19 inwardly and the fingers engaging the knuckles, amplify the swinging movement of the jaw 19 and cause it to swing upon its pivot pin 20, whereby it is closed. As the gripping jaw approaches its closing position 40 the face of the hook 21 rides over the latching bar 29 and finally engages under the same. When the jaws are closed as is indicated in full lines in Figs. 2, 3 and 4, the tips of the fingers will register with the outer ends of the knuckles so that the jaws are free to move independently to a limited extent.

It is not essential to the invention that the jaw 17 acts to swing the jaw 19 or that the knuckle joint be employed. However an important feature of the invention is the pivoting or hinging of the two jaws together and the fulcruming of one of the jaws in the head, together with the displacement of the 55 fulcrumed jaw to clamp the pipe.

In Fig. 5 I have shown a form in which the ears 16 have rounded ends 16' co-acting with the jaw 19 and the latter is provided with arcuate fingers 50 swinging into recesses 51 in the head. When the jaw 19 is opened the fingers 50 are swung into the path of the pipe which engages the same thus swinging the jaw 19 into a closed position when the wrench is moved toward the pipe.

In Fig. 6 the fingers 50 are combined with the knuckle joint in an auxiliary capacity. When the jaw 19 is opened the jaw 17 is swung from the seat and the fingers 50 are swung in advance of the jaw 17. Thus when the wrench is presented to the pipe the fingers 50 are first engaged and should the knuckle joint fail to function, said fingers will close the jaw 19.

Where the knuckle point is used the swing of the jaw 19 is amplified thereby and when the fingers 50 are employed they control the swinging of the jaws.

After the pipe is gripped in the jaws it is necessary to firmly engage them with the pipe so that the latter will be turned when the wrench is swung. Between the cheek plates 11 I mounted an eccentric or cam 32 and I also provide the inner edge of the actuating jaw 17 with a cam face 33. An elongated handle 34 is attached to the cam for the purpose of swinging the same and also to manipulate the wrench. In the cam is provided a pair of diverging slots 35 thru which pins 36 pass, the latter being immovable in the plates 11.

It will be seen that one pin acts as a fulcrum and the slot of the other pin permits the cam to undergo a limited arcuate movement, the cam thus becoming an eccentric and riding along the cam 33, whereby the jaw 17 is displaced outwardly and caused to clamp the pipe.

The jaws being latched around the pipe and one being fulcrumed to the head, while the other is fulcrumed to the first named jaw, it would be impossible to displace the jaw 17 unless compensation was provided at the pin 18. For this purpose the jaw 17 has a slot 17' thru which the pin 18 passes and this permits said jaw to undergo a limited sliding movement when displaced by the cam.

The pair of slots 35 and pins 36 permit the cam to be swung in either direction and thus the wrench is reversible by merely swinging the handle 34. The advantage of the eccentric action of the cam and the gradual and even displacement of the jaw 17 will be readily apparent. This wrench 115 will not crush the pipe or casing and yet will be positive and quick in action.

When placing the wrench on the pipe it is desirable to hold the handle against swinging and while any suitable means may be used for this purpose, I found a spring plunger to give satisfactory results. On one side of the handle I mount a box 37 adjacent the plate 11 which is provided with a socket 38 for receiving a plunger bolt 39 mounted to slide in the box. A plunger link 41 is pivoted to the end of the bolt and extends thru a slotted bracket 40 mounted on the handle. A coiled spring 42 is confined on the link between the bolt and the 130

bracket and acts to seat the bolt in the socket. A finger lever 43 is pivoted on a bracket 44 on the side of the handle and the link is eccentrically pivoted to said lever, which 5 when the bolt is seated, lies along the handle in approximately parallel relation to the link. When it is desired to withdraw the bolt 39 from the socket 38 the lever is swung outwardly, whereby the link is pulled and 10 the bolt retracted. By swinging the lever to its full extent the parts are held in unlatched position, whereby the lever is free to swing and actuate the cam 32.

Various changes in the size and shape of 15 the elements as well as modifications may be made within the scope of the appended claims.

What I claim, is:

1. In a wrench, a head having a seat, an 20 actuating jaw pivoted to the head and swinging relatively of said seat, a gripping jaw pivoted to the actuating jaw and being swung thereby, a knuckle joint formed between the gripping jaw and head for amplifying the closing movement of said jaw, and means carried by the head for fastening the gripping jaw in its closed position.

2. In a wrench, a head having a seat, an actuating jaw pivoted to the head and 30 swinging relatively of said seat, a gripping jaw pivoted to the actuating jaw and being swung thereby, a knuckle joint formed between the gripping jaw and the head for amplifying the closing movement of the said 35 jaw, means for fastening the gripping jaw in its closed position, a cam mounted in the head and eccentrically engaging the actuating jaw for displacing the same into clamping engagement with a pipe or the like, and 40 a handle mounted in the head and connected with the cam.

3. In a wrench, a head having a seat, an actuating jaw pivoted to the head and swinging relatively of said seat, a gripping 45 jaw pivoted to the actuating jaw outwardly of the head and being swung by the actuating jaw, a knuckle joint provided between the head and the gripping jaw and located relatively between the pivots of the jaws, 50 means for fastening the gripping jaw in its closed position, and means for displacing the actuating jaw into clamping position with relation to said seat and said gripping jaw and including a handle.

55 4. In a wrench, a head, a pair of jaws hinged together, one of said jaws being pivoted on the head, the last named jaw swinging the first named jaw when swung itself, a self latching keeper carried by the 60 head and engaged by one of the jaws, and means carried by the head and co-acting with one of the jaws for amplifying the swinging of the latter when the jaws are swung to engage with the keeper.

65 5. In a wrench, a head, a pair of jaws

hinged together, one of said jaws being pivoted on the head, the last named jaw swinging the first named jaw when swung itself, a self latching keeper carried by the head and engaged by the first named jaw, 70 means carried by the head and co-acting with the first named jaw for amplifying the swinging of the said jaw when the jaws are swung, a handle, and means actuated by the handle and mounted in the jaw for displacing the last named jaw into clamping engagement with the article gripped by the 75 jaws.

6. In a wrench, a head comprising spaced cheek plates having a seat, a lug provided on the head on one side of the seat, a pair of ears formed on the head on the other side of the seat, an actuating jaw pivoted between the ears and swinging thru the seat, the outer end of the actuating jaw projecting beyond the ears, a gripping jaw having one end pivoted on the projecting end of the actuating jaw, a finger carried by the gripping jaw, a knuckle on one of the ears for engagement by the finger, a latch hook 90 on the free end of the gripping jaw, a spring actuated keeper pivoted on the lug and engaged by the hook, a handle, and means mounted in the head and connected with the handle for operating the actuating jaw to 95 clamp an article within the jaws.

7. In a wrench, a head comprising spaced cheek plates having a seat, a lug provided on the head on one side of the seat, a pair of ears formed on the head on the other side of the seat, an actuating jaw pivoted between the ears and swinging thru the seat, the outer end of the actuating jaw projecting beyond the ears, a gripping jaw having one end pivoted on the projecting end of the 100 actuating jaw, a finger carried by the gripping jaw, a knuckle on one of the ears for engagement by the finger, a latch hook on the free end of the gripping jaw, a spring actuated keeper pivoted on the lug and engaged by the hook, a handle, a cam mounted in the head between the cheek plates and having a pair of diverging slots, pins fastened in the plates and passing thru the slots of the cam, the actuating jaw having a cam 105 face engaged by the cam, the handle being connected with the cam, and means for detachably connecting the handle with the head.

8. In a wrench, a head having a seat, a 120 curved actuating jaw fulcrumed in the head and swinging relatively of the seat, said jaw having a limited sliding movement relative to its fulcrum, a gripping jaw pivoted to the actuating jaw, a latch carried by the 125 head and engaged by the gripping jaw, and means for displacing the actuating jaw to clamp an article in the jaws.

9. In a wrench, a head having a seat, a 130 curved actuating jaw fulcrumed in the head

and swinging relatively of the seat, said jaw having a limited sliding movement relative to its fulcrum, a gripping jaw pivoted to the actuating jaw a latch carried by the head and engaged by the gripping jaw, a cam eccentrically pivoted in the head and engaging the actuating jaw to displace the same, and a handle connected with the cam.

10. In a wrench, a head having a pair of ears at one side, an actuating jaw fulcrumed between the ears and having one end projecting beyond the ears, the actuating jaw having a limited sliding movement relative-

ly of its fulcrum, a gripping jaw pivoted on the projecting end of the actuating jaw, a latch on the head opposite the ears, the gripping jaw having means for closing it when the wrench is engaged with a pipe, the gripping jaw also having a hook for engaging the latch, said jaw swinging relatively about the ears, and means including a handle for displacing the actuating jaw both slidely and rotatively relatively of its fulcrum. 15 20

In testimony whereof I affix my signature.
JOSEPH W. KAOUGH.
